UNITED STATES PATENT OFFICE.

GEORGE MEIER, OF CALDWELL, NEW JERSEY, ASSIGNOR TO ISRAEL J. TOMBACHER, OF KINGS COUNTY, NEW YORK, AND HARRY M. FELTENSTEIN, OF CHICAGO, ILLINOIS, DOING BUSINESS AS M. EISENBERG & SON, OF NEW YORK, N. Y.

DESIGN FOR A BRACKET FOR LIGHTING FIXTURES OR SIMILAR ARTICLE.

Application filed October 4, 1921. Serial No. 505,401. Term of patent 3½ years.

To all whom it may concern:

Be it known that I, GEORGE MEIER, a citizen of the United States, and a resident of Caldwell, county of Essex, and State of New Jersey, have invented a new, original, and ornamental Design for a Bracket for Lighting Fixtures or Similar Article, of which the following is a specification, reference being had to the accompanying drawing, forming a part hereof.

Figure 1, in the drawing, shows a side ele-

vation of the bracket and Figure 2 shows a front elevation of the bracket with parts broken away.

I claim:

The ornamental design for a bracket for lighting fixtures or similar article, substantially as shown.

GEORGE MEIER.
